UNITED STATES PATENT OFFICE

2,049,627

STOCK QUOTATION SYSTEM

Harold C. Robinson, Chicago, and John I. Bellamy, Brookfield, Ill., assignors, by mesne assignments, to Associated Electric Laboratories, Inc., Chicago, Ill., a corporation of Delaware

Original application July 10, 1931, Serial No. 549,969. Divided and this application September 6, 1932, Serial No. 631,906

11 Claims. (Cl. 177—353)

The present invention relates to stock-quotation systems, but is concerned more particularly with systems of this kind wherein a central-station transmitter comprising a register sender is employed to transmit stock quotations to a plurality of receivers, each receiver having associated therewith groups of indicating devices to indicate the received stock quotations.

This application is a division of our application 549,969, filed July 10, 1931. In the parent application, the main object, broadly stated, is the production of a new and improved transmitting and receiving system for transmitting information regarding the selling price of stocks and similar commodities, so that such prices may be received and set up on indicators at a plurality of places.

This divisional application covers the novel features of the new and improved register sender or transmitter used at the central transmitting station of the system.

The system disclosed may be considered an improvement on the systems disclosed in the following applications: Bellamy et al., Serial No. 378,208, filed July 15, 1929; Bellamy, Serial No. 413,205, filed December 11, 1929; Nelson et al., Serial No. 445,746, filed April 19, 1930; Robinson et al., Serial No. 462,114, filed June 18, 1930. These United States applications correspond to 30 British Patents Nos. 358,889, 368,369, 376,754, and 384,671, respectively.

General description

As pointed out in the prior applications, the 35 common method employed by stock brokers is to post the stock-market prices on a blackboard so that they and their customers may readily see them. Now, in order to secure a quicker and more efficient posting of the stock-market quotations, it is proposed in the said prior application to provide each of a plurality of stock-broker's offices with a mechanical indicating board, with a separate group of indicators on each board for each stock in which the broker 40 is interested, and to furnish receiving and indicator-controlling apparatus at each receiving board, all controlled from a common transmitting station.

As pointed out in the parent application, the 50 present system contains the following outstanding features:

1. In order to increase the number of stock quotations to a maximum that can be sent over the transmission line, with a predetermined frequency of impulses, each of the two working

transmitters at the transmitting station has been modified so that the other transmitter can start sending a new quotation immediately following the last digit of a quotation, with the same interval elapsing between quotations as elapses between successive digits of the same quotation. By this arrangement, the two transmitters operate alternately to send impulses continuously over the transmission line during the time when the stock market is most active. 10

2. In order to prevent a second quotation from being sent too soon from the same transmitter when the other is not in operation, counting means is provided in each transmitter to count off the same number of impulse periods that 15 would be taken up by the other transmitter in sending a quotation before permitting the same transmitter to start a new quotation. By this arrangement, a given transmitter sends its quotations at the same rate and with the same minimum spacing between quotations regardless of whether the other transmitter is working or not, and the corresponding local senders in the receivers are, therefore, given time to set up each 20 quotation on the indicators.

3. In order to permit the operator who is setting up quotations on a transmitter to operate at the highest efficiency, arrangements are made for unlocking the stock-range keys (which are locked up while a quotation is being transmitted from her transmitter, in order to prevent the operator from setting up quotations faster than they are being sent out), as soon as the last digit of a quotation has been transmitted, and without waiting for the inter-quotation timing operation to be performed. In this way, the operator can set up the final digit of a new quotation as soon as the last digit of the previous quotation has been sent out, which arrangement permits the operator to keep farther ahead 40 of the sending operation, and it allows the operator to take a slightly longer time in setting up more difficult quotations without causing the transmitter to wait while the next quotation is being set up. 45

4. In the present system, the number of digits or character combinations in a quotation has been reduced from ten to eight by eliminating the hundreds digit and by curtailing the price-range digit to a small number of values and combining it with the stock-range digit in a single character combination, thereby shortening the sending time of each quotation. In line with this arrangement, the open, high, low, and last indicator groups at the receiver are 50 55

equipped with tens, units, and fractions indicators only. The previous-close group, however, is equipped also with a hundreds register, and special arrangements are provided for setting this hundreds register, as will be hereinafter described.

5. In the stock-quotation receivers, the counting relays used to transfer the impulsing conductors to the several digit registers as the successive digits of a quotation are received are automatically brought into normal position responsive to the final digit of a quotation, so that they are immediately in readiness to receive the first digit of the following quotation, which as stated hereinbefore is sent immediately and with no more pause than occurs between successive digits of the same quotation.

6. In order to reduce the receiving apparatus to a minimum, a single receiver with two sections is provided instead of two separate receivers, as heretofore, and the relay groups which register the stock-code and stock-range digits are made common to the two sections, while suitable connecting relays are provided to associate the common registers with whichever section corresponds to the transmitter from which a quotation is received.

In one embodiment, separate groups of transfer relays are associated with the two local senders for controlling the registration of the price digits, together with a connecting relay for each group to connect up such groups for operation, depending upon which local sender is to be operated.

35. In an illustrated modification, the same set of digit-transfer relays is used for both groups of price-digit registers, thereby reducing the number of transfer relays and simplifying the associated circuits, while suitable connecting relays are provided for connecting the branch registering conductors as controlled by the price-digit transfer relays) to the appropriate one of the two groups of price-digit registers.

7. In order to increase the speed at which the transfer from one digit group to another is made, the conductors over which the impulses are received are connected up to the digit registers by contacts of the digit-counting relays themselves instead of through contacts of separate connecting relays controlled from the digit-counting relays.

8. A special feature of the modified receiver is that the number of digit-counting transfer relays has been halved by providing a set of impulse-distributing relays to distribute the impulses to the transfer relays. In connection with this arrangement, one of the impulse-distributing relays carries contacts for connecting the group of conductors over which impulses are received to two branch groups alternately, permitting one branch group to be connected up to a register in readiness for operation while the other branch group is connected to the main group. In this way, the connections to the digit registers are prepared in advance to the two branch groups of conductors, and the actual transfer from one register to another is made by one of the impulse-distributing relays.

9. In order to reduce the number of relays required for selecting the desired stock, circuit arrangements are provided for making the hundreds relays common to both sections of the receiver, while separate tens relays are provided for each section.

75. 10. In order to provide a more reliable oper-

ating circuit for the transfer relays, contacts are provided on all four of the impulse-receiving relays for controlling the application of potential to a transfer-control impulse conductor each time a digit is received, instead of providing transfer relays operated in series with the relays of the digit registers themselves, as in the application of Robinson et al. hereinbefore referred to.

11. In order to reduce the number of slow-acting holding relays from four to one, contacts are provided on each of the impulse-receiving relays for controlling the circuit of a single slow-acting holding relay, instead of the arrangement in the above-mentioned application of Robinson et al., wherein a separate slow-acting holding relay is connected to each of the four incoming impulse conductors.

12. A feature of the stock-quotation receiver disclosed herein is that an auxiliary indicating board may be connected up in a different location in the broker's premises so that it will display the same quotations as are displayed on the main indicating board, and that a so-called executive's board may be connected up to the receiver to show the current selling price, or last price, only of any desired number of stocks.

13. A feature of the stock-quotation receiver employed in the system disclosed herein is that the current is supplied by a motor generator instead of from a storage battery. This lowers the cost of the receiver considerably, as a motor generator is lower in cost than a storage battery and a charger, and it enables the potential to be removed from the relays and other apparatus of the receivers and indicating boards under the control of the central transmitting station. In connection with this arrangement, it may be pointed out that the motor generators in all the receiving stations are automatically started responsive to the application of normal line current at the transmitting station on the opening of the business day, and is automatically terminated responsive to the transmission of a regular impulse over the line, with the normal line current not replaced following the impulse.

Other objects and features of the invention, mainly incidental to those hereinbefore stated, will become apparent upon a further perusal of this specification.

Referring now to the drawings, comprising Figs. 1 to 23, they show a sufficient amount of equipment in a stock-quotation system embodying the features of the invention to enable the invention to be understood.

Figs. 1 to 5, taken together, show a transmitter T_1 at the transmitting station;

Fig. 6 shows the repeater R , which repeats the impulses received from the transmitters T_1 and T_2 to the lines outgoing to the stock-quotation receivers;

Figs. 7 to 13 show one of the receivers;

Figs. 14-16 show a modification of the portion of the receiver shown in Figs. 7-9;

Figs. 17 and 18 show one of the digit indicators used at the quotation-indicating boards;

Figs. 19, 20, and 21 are tables showing the codes employed in transmitting stock digits, stock-range digits, and price digits, respectively;

Fig. 22 is a layout drawing showing how the sheets on which Figs. 1 to 13 are drawn should be arranged in order for the system to be understood best; and

Fig. 23 is a layout drawing similar to Fig. 22,

showing Figs. 14-16 replaced by Figs. 7-9 to disclose the modified receiver.

As in the prior, pending applications referred to, the system disclosed herein is arranged on the assumption that two operators will be required to set up the quotations at the transmitting station. Each operator is provided with a separate transmitter. Since the stocks are identified by the letters of the alphabet (some stocks being identified by a single letter, others by means of two letters, and still others by means of three letters) the division of labor between the two operators may be conveniently made by assigning to one operator all stocks identified by the letters A to M and all stocks having the initial letter A to M, and by assigning the remaining stocks to the other operator, as is explained more fully in the prior applications referred to.

A receiver is provided in the office of each subscribing broker. Each receiver comprises two sections, corresponding to the two transmitters at the transmitting station, as well as to the two stock groups, respectively. Each section of the receiver contains a separate local sender for restoring and reoperating the quotation indicators on the indicating board.

On the indicating board, indicators of the type shown in Figs. 17 and 18 are arranged in groups of sixteen, one group for each stock being dealt in by the broker in whose office the indicating board is installed. In addition to the regular or main indicating board, a broker may desire to have an auxiliary indicating board installed in a separate room of his office for the use of a separate group of customers. Moreover, the executive's board is provided for the use of one or more of the executives of the stock brokerage firm, and may be located in one of the private rooms of the broker's office.

Fig. 13 shows one group of indicators on each of the three indicating boards above-mentioned. In the case of the main board MB and the auxiliary board AB, the registers are arranged in five horizontal rows, with four registers in the top and three registers in each other row. In the top row, the first register indicates the hundreds digit, and in any other row the registers indicate the tens, units, and fractions digits, respectively. The top row of registers (PC) is arranged to indicate the previous closing price; the second row (OP) indicates today's opening price; the third row (HI) indicates the high price of the day; the fourth row (LO) indicates the low price of the day; and the bottom and fifth row (LA) indicates the last price.

At the executive's board EB, only three indicators are provided for any stock, these three indicators giving the tens, units, and fractions digits, respectively, of the last price at which the corresponding stock sold.

Each receiver comprises receiving apparatus for receiving the digits transmitted from the central transmitting station, together with group-selecting and connecting apparatus for connecting up the section of the receiver for operation corresponding to the operating transmitter and consequently corresponding to the stock group from which the quotation is coming. Each receiver section comprises apparatus for selecting the desired stock group and for operating the indicators therein to set up the price digits of the received quotation.

A three-digit code is assigned to each stock whose quotations are to be transmitted by a given transmitter, and translating arrangements

are provided (as disclosed in the Robinson et al. application hereinbefore referred to) for translating the stock-letter designation of stock to the assigned group of code digits, which code digits are transmitted along with the quotation to enable the receiver to select the corresponding group of stock registers on the indicating board. 5

The transmitter

Referring now particularly to Figs. 1 to 5, the 10 arrangement of the transmitter T1 will be explained generally. The portion of the transmitter used to set up the stock letters and to translate them into the stock-code digits is not shown but may be identical with the apparatus used for 15 this purpose in the application of Robinson et al. referred to and disclosed in Figs 1 to 3 therein. Accordingly, for a complete disclosure of the transmitter T1, Figs. 1 to 3 of the said Robinson et al. application may be placed to the left 20 of Figs. 4 and 5 of the present drawings.

In the present drawings, Fig. 1 shows a group of price-digit keys, by means of which the price digits of a stock quotation are set up; and a set of stock-range keys, by means of which a 25 range digit is set up to direct the quotation to the proper row or rows of registers in a selected stock group of indicators and to indicate the number and denomination of price digits contained in a quotation. 30

Each transmitter has two register sets and a sender. Register set No. 1 comprises the registers of Figs. 5, 4, and 3 (SH, ST, SU, PT, PU, PF, and SR), while register set No. 2 is indicated by the rectangle at the bottom of Fig. 2, 35 and is a duplicate of register set No. 1.

In the register set No. 1, the registers SH, ST, and SU register the stock-hundreds, stock-tens, and stock-units digits of the translated stock code; registers PT, PU, and PF of Figs. 4 and 3 40 register the tens, units, and fractions-price digits, set up successively through the medium of the price-digit keys of Fig. 4; and the stock-range register ST of Fig. 3 registers the stock-range and price-range digits set up on the stock- 45 range keys of Fig. 1.

The sequence relays 202 and 203, Fig. 5, are common to both register sets and are arranged to be operated alternately to associate the register sets alternately with the apparatus used to 50 set up the digits on the registers, including the digit keys of Fig. 1.

The sender consists of the apparatus of Figs. 3 to 5 to the right of the tie cable 204 (which is used to interconnect the two register sets) and 55 is arranged to control the sending relays 31-39 of register set No. 1 and the corresponding relays of register set No. 2 to send out the registered digits. 60

The receiver

Referring now to Figs. 7 to 13, the arrangement of the receiver will be explained generally. This receiver receives all quotations transmitted from the central station, as contrasted with the arrangement disclosed in the prior applications 65 hereinbefore referred to, wherein separate receivers are employed for responding to quotations sent out concerning the two main groups into which the stocks are divided. The receiver shown in Figs. 7 to 13, however, has separate 70 sections for handling quotations concerning the two stock groups, with as much of the receiving apparatus as is considered practicable arranged to be common to the two receiver sections. The apparatus of Figs. 7 and 8, together with the 75

relay apparatus at the top of Fig. 10 and the indicating boards of Fig. 13, is common to both receiver sections. The remaining apparatus shown in detail is individual to section 1, while the apparatus individual to section 2 is indicated by the rectangle shown at the bottoms of Figs. 11 and 12.

The apparatus shown in Fig. 7 includes the four impulse-receiving relays, 701-704, the motor generator MG and associated equipment controlled by relays 705 and 706, and the relays 709-711, used to select section 1 of the receiver, together with relays 709'-711', used to select section 2 of the receiver.

The apparatus shown in Fig. 8 includes the registers SH, ST, SU, and SR, which record the stock-code digits and stock-range and price-range digits for both sections of the receiver. Each of these registers include relays A to D, and the registers are associated with the impulse conductors A to D in group 731 under the control of the transfer relays 801-807.

The apparatus shown in Fig. 9 includes the registers PT, PU, and PF which register the price digits when section 1 of the receiver is in use. These registers are rendered effective whenever the connecting relay 901 is energized under the control of relays 709-711, Fig. 7.

The apparatus of Fig. 10 includes the stock-selection relays, together with the intermediate distributing frame IDF and the connecting relays 1001 and 1001'. Of the stock-selection relays, there are six hundreds relays, of which H1, H2, and H6 are shown, and there are sixty tens relays for each section of the receiver, of which the relays T12, T21, and T60 of section 1 are shown, together with tens relays T'12, T'21, and T'60 of section 2. The connecting relay 1001 is operated over conductor 720 to connect up the conductors extending to the contacts of the tens relays of section 1 when the quotation is coming from transmitter T1, and relay 1001' is operated over conductor 720' of the second section whenever the quotation being received is coming from transmitter T2.

Fig. 11 shows the section 1 local sender, comprising relays 1118-1135, together with the impulse machine IM, operated by motor 1117 and common to both sections of the receiver. The upper set of contacts of the impulse machine IM control the section 1 local sender, while the lower set of contacts control the section 2 local sender.

Fig. 12 shows the stock-range relays 1202-1210, together with the connecting relay 1201, which is operated to connect these relays and price-range relay 1118 of Fig. 11 to the contacts of the relays in the stock-range register SR, Fig. 8, whenever a stock quotation relating to a stock handled by section 1 is being received. These stock-range relays are operated to determine the row or rows of indicators in a selected stock group to be operated.

Fig. 13 shows the main indicating board MB, the auxiliary indicating board AB, and the indicating board EB, used by executives. Only one stock group and associated stock relay is shown at each board.

It may be pointed out that the connections incoming to the armature springs of the stock relays, the stock relay 1301 for example, is made preferably through jack contacts, so that any stock relay may be inserted into either of two sets of jack contacts to associate it with the multiple of either of the two receiver sections.

In this way, any group of indicators may be assigned to any stock in either stock group.

It is to be noted that each of the stock relays, 1301, 1302, and 1303, is shown in association with the stock multiple of section 1. The contacts 5 of the multiple of section 2 are shown just below the contacts of the stock multiple of section 1, and the jack contacts are preferably so arranged that the position of the relay may be shifted only slightly to connect the relays to the multiple 10 contacts of the other section.

The motor generator MG obtains power from the incoming commercial power leads, and it supplies current to the receiving apparatus through the bus-bars 707 and 708.

The electro-polarized receiving relays 701, 702, 703, and 704 are of the type disclosed in the United States Patent No. 1,673,884, granted June 19, 1928, to Harold C. Pye. A relay of this type is provided with a locally energized polarizing 20 winding which cannot operate the relay alone, because of the magnetic structure, but polarizes the relay so that it is operated and released under control of the line current.

General arrangement of the system

Referring now particularly to Fig. 6, the general arrangement of the system will now be explained. It is to be noted that the conductors A to D outgoing from the transmitters T1 and 30 T2 are multiplied together and extend to relays A to D (606-608) of the repeater R. This repeater is arranged to repeat the impulses from either operating transmitter to each of a plurality of lines, of which the lines 1 and 2 are 35 shown. The lockout relays 601 and 602 are controlled from the transmitters T1 and T2, respectively, so that while one transmitter is operating the other is locked out and its operation prevented.

Each of the lines extending to the right from the repeater R may be common to a plurality of receivers, the receiving relays of the several receivers of a line being connected in series, with the end of each line connected to ground 45 beyond the last receiver on the line. It is to be noted that each line is normally connected to the positive line battery through contacts of the repeating relays and contacts of the knife switch 604. By this arrangement, a normal biasing current flows over the line during the time no impulses are being transmitted and between successive impulses while impulses are being transmitted. This normal biasing line current maintains the polarized receiving relays normally actuated in the receivers, and it serves to reactivate them following their restoration responsive to an impulse of current delivered from the negative line to battery.

The relay 603, together with the controlling 60 push-button 609, is provided for the purpose of controlling the starting and stopping of the motor generator at the receiver, in a manner to be explained in detail hereinafter.

Detailed description

The system having been described generally, a detailed description of the operation of the apparatus shown will now be given. For this purpose a description will be given of the operations involved when the operator at the transmitter T1, shown in Figs. 1 to 8, sets up the quotation BBA-041-LA (TUF). The stock-letter prefix BBA is a prefix by means of which the stock is identified to the operator, the digits 75

0, 4, and 1 on the quotation indicate no tens, four and one-eight dollars; and the suffix LA(TUF) is added by the operator to indicate that the quotation is to be set up as the last price, and that the tens, units, and fractions digits are being transmitted.

Stock registration

To set up this quotation, the operator first 10 operates the letter keys to set up the prefix letters B, B, and A on the stock-letter registering apparatus (not shown), which relays are locked operated by the ground potential applied to conductor 512 through contacts of relays 205 and 15 206 and contacts of the energized relay 202 (assuming register set No. 1 to be in use and relay 202 therefore energized, as shown).

Price registration

20 In order to set up the price digits 0, 4, and 1, the operator employs the price digit-keys of Fig. 1.

It is to be noted that the conductors A to D extending to the right from the price-digit keys 25 of Fig. 1 are now connected through contacts of connecting relay 402 to the register relays A to D of the price-tens register PT. Accordingly, when the digit—"0" key of Fig. 1 is depressed, a circuit is closed over the associated conductors 30 A, B, and D (in accordance with the code given in the code table, Fig. 21, wherein the digit 0 is represented by characters A, B, and D), for relays A, B, and D of the price-tens register PT, Fig. 4. When relays A, B, and D of register PT 35 operate, in addition to preparing sending circuits at their upper contacts, they close locking circuits for themselves at their respective inner armatures through the transfer relay 401 to the locking conductor 210, grounded at this time 40 through the inner contacts of the error relay 206, Fig. 2, and the inner contacts of the operated relay 202. Therefore, when the price digit key "0", Fig. 1, is released, relay 401 operates in 45 series with the associated relays A, B, and D. Upon operating, relay 401 opens the circuit of relay 402 and closes a circuit through contacts of relay 305 for connecting relay 306 of the price-units register PU. As a result, relay 305 falls back and disconnects relays A to D of the 50 price-tens register PT, and relay 306 operates and connects up the relays A to D of the price-units register PU.

When the operator depresses the digit—4 key, Fig. 1, to set up the units digit 4, relay B of 55 the price-units register PU operates and locks itself to conductor 210 in series with transfer relay 305, with the result that relay 305 operates when the key is released and brings about the deenergization of connecting relay 306 and the energization of connecting relay 304.

When the operator depresses the digit—1 key to set up the fractions digit 1, relay D of the price-fractions register PF operates through contacts of the operated relay 304 and closes a 60 locking circuit for itself through transfer relay 303, which transfer relay operates when the digit key is released, opening the circuit of connecting relay 304.

Stock-range registration

70 The operator sets up the range suffix LA (TUF) by depressing the one of the stock-range keys of Fig. 1 bearing this designation. When this key is depressed, ground potential is applied 75 to the associated conductors A and D, operating

relays A and D of the stock-range register SR through contacts of the operated connecting relay 302. Relays A and B close locking circuits for themselves through the transfer relay 301, with the result that relay 301 is operated to open the circuit of connecting relay 302 at its inner-upper armature when the stock-range key is released.

Stock translation

When the transfer relay 401 of the price-tens register PT, Fig. 4, operates upon the registration of the price-tens digit 0, as hereinbefore described, it places ground potential at its upper contact on conductor 209, thereby extending 15 ground potential through the lower contacts of start relay 205 to the translation-start conductor 511, extending to the stock registers (not shown). Responsive to the application of ground potential to conductor 511, the registered 20 stock-letter prefix BBA is translated into a three-digit stock code, which code, it is assumed, is 122. Accordingly, the first, second, and second conductors in groups CD1, CD2, and CD3, respectively, of Figs. 5 and 4, are grounded. 25 With connecting relays 503, 502, and 504 operated, as shown, the grounding of the above-mentioned conductors results in the energization of relay 1 of the stock-hundreds register SH, of relay 2 of the stock-tens register ST, 30 and relay 2 of the stock-units register SU. Each of these relays closes its associated digit contacts and closes a locking circuit for itself at its inner contacts to the now grounded locking conductors 210.

In the register set No. 1, Figs. 3 to 5, with a register relay in each of the registers SH, ST, and SU operated, a circuit is prepared from ground through the contacts of the three operated register relays and over conductor 405 for 40 start relay 205, which circuit is held open, however, at the lower contacts of transfer relay 301 of the stock-range register SR until relay 301 is operated upon the completion of the registration of the stock-range digit, it being kept in 45 mind that the translation takes place responsive to the registration of the first price digit, on the register PT of Fig. 4, while the stock-range digit is the last digit to be registered.

Connecting the register set to the sender

When the transfer relay 301 of the stock-range register SR operates as hereinbefore described, upon the registration of the stock-range digit, it closes a circuit at its inner-lower armature for connecting relay 307, whereupon relay 307 connects the sending relays 32-38 of register set No. 1 to the sender preparatory to the operation of the sending relays 32 to 38 to send out the registered digits.

Releasing the stock registers

As a further result of the operation of relay 301, the circuit prepared over conductor 405, upon the completion of the stock translation, for 65 start relay 205 is closed at the lower contacts of relay 301, whereupon start relay 205 operates, and at its lower armature removes ground potential from the translation-start conductor 511, thereby opening the circuit of the stock-translating relay (not shown), permitting this relay to fall back. Start relay 504 also removes ground potential from the locking conductor 512, whereupon the operated relays in the stock registers (not shown) fall back.

Transfer to register set No. 2

As a further result of its operation, start relay 205 makes an additional application of ground potential to the register locking conductor 210 of register set No. 1 by way of the sender branch 208 of the locking conductor, to ground by way of contacts of the relay 22 of the sender; and, at its inner-upper armature, relay 205 closes a circuit for relay 203, whereupon relay 203 operates and at its inner-upper armature opens the holding circuit of relay 202, whereupon relay 202 falls back and closes a holding circuit for the upper winding of relay 203. With relay 202 deenergized and with relay 203 operated, register set No. 1 is disassociated from the apparatus to the left of cable 201, and register set No. 2 is associated therewith, ground potential being removed from connecting conductor 211 by relay 202, and ground potential being placed on the corresponding conductor 211' of register set No. 2 by relay 203.

At its middle-upper armature, relay 203 replaces ground potential on the stock-register locking conductor 512, by way of contacts of the error relay and start relay (not shown) of register set No. 2, corresponding to relays 206 and 205 of register set No. 1. In addition, the error relay 206 of register set No. 1 is disconnected, and the corresponding relay of register set No. 2 is connected up to the error conductor 103. It will be understood, of course, that the various conductors, with the exception of conductor 103, entering Figs. 3 to 5 from the left, are multiplied into register set No. 2 by means of the multiplying cable 201.

Stock-range keys locked

As a further result of the operation of start relay 205, start conductor 207 is grounded, and a circuit is thereby closed for the locking magnet 111, associated with the stock-range keys. Responsive to the closing of this circuit, locking magnet 111 energizes, and, by means of a mechanical interlocking device (not shown), locks the stock-range keys so that no one of them can be depressed for the time being. The lamp 112 becomes lighted to indicate to the operator that the start circuit has been closed and that the stock-range keys are locked.

Setting the register set No. 2

When the operator depresses her keys for the next quotation, relays in the stock registers (not shown) are operated as before, and during the course of the setting-up of the quotation a transfer of the translated stock designation takes place as described hereinbefore, except that the translated digits are transferred to the stock registers in register set No. 2 in place of the registers SH, ST, and SU of register set No. 1, because connecting conductor 211 is ungrounded, while connecting conductor 211' is grounded, as hereinbefore described. Also, the manipulation of the price-digit keys of Fig. 4 results in the setting up of digits in register set No. 2 in place of in register set No. 1, for the same reason. It will be recalled that the stock-range keys are locked for the time being, and the result is that, if the operator is able to set up the main portion of the quotation before the transmitter has sent out the quotation registered on register set No. 1, she is prevented from setting up the stock-range digit of the next quotation until the locked condition of the stock-range keys have been terminated.

Starting the sender

Since the two transmitters use the common transmitting lines alternately, arrangements must be provided for regulating the starting time of the sending operation of one transmitter with respect to the sending operation of the other transmitter. For this purpose, the two lockout relays, 601 and 602, Fig. 6, are provided, one for each transmitter, so as to prevent the closing of the start circuit for either transmitting during the operation on the other transmitter until the operation of the operating transmitter has proceeded sufficiently far that the newly started transmitter will not send the first digit before the operating transmitter has sent out the last digit.

The application of ground potential to conductor 207 by start relay 205, Fig. 2, in addition to bringing about the locking of the stock-range keys as hereinbefore described, prepares a circuit over conductor 526, by way of contacts of relay 20, Fig. 4, for relay 601, Fig. 6. Relay 601 cannot operate for the time being, however, if relay 602 of transmitter T2 is in an energized condition. When it operates, relay 601 opens a point in the circuit of relay 602 so as to prevent a premature operation of relay 602 of transmitter T2, and it places ground potential on the incoming-start conductor 525 of the sender of the transmitter T1.

With conductor 525 grounded, as soon as interrupter 12 arrives in closed position, ground potential is extended through contacts of relays 27, 26, 24, 22, 20, 18, 16, and 14 to relay 13. Relay 13 thereupon operates and locks itself to conductor 527, which is now grounded by virtue of its connection with the grounded start conductor 525, through contacts of relay 27, Fig. 3. The locking circuit of relay 13 includes the winding of relay 14, but relay 14 does not operate as long as the interrupter 12 remains closed, because ground potential is connected to both terminals of its winding. As soon as interrupter 12 opens, relay 14 energizes in series with relay 13, in the locking circuit of the latter relay, and transfers the operating conductor to the counting pair comprising relays 15 and 16. At its inner left-hand contacts, relay 14 applies ground potential to the incoming-start conductor 525, so as to maintain this start conductor grounded independent of relay 601 until the sender has finished its operation. At its left-hand armature, relay 14 extends ground potential from the grounded conductor 527 by way of contacts of relay 15 to sending relay 31, whereupon sending relay 31 operates preparatory to sending the preliminary character combination or digit for identifying the transmitter from which the quotation is coming. This transmitter-identifying digit is transmitted over conductors 521-524 by interrupter 11, and while interrupter 12 is in open position. It may be pointed out that the interrupters 11 and 12 are preferably mounted on the same shaft, thereby avoiding angular displacement.

As the interrupter 12 continues to operate, one of the remaining counting relays 15 to 27 is operated on each closure of the interrupter, and another of the relays is operated on each opening of the interrupter. It is to be noted that the interrupter 11 sends an impulse in the latter part of each closed position of the interrupter 12 and that it sends an impulse in the latter part of each open position of the inter-

rupter 12. Accordingly, interrupter 11 grounds the sending conductor 504 following the operation of each succeeding one of the counting relays 15 to 27.

When relay 15 is operated by interrupter 12, following the transmission of the transmitter-identifying digit, it opens the circuit of sending relay 31 and closes a circuit for sending relay 32 through contacts of the connecting relay 307 of register set No. 1. Accordingly, relay 31 falls back and relay 32 operates, with the result that the next digit of the quotation is transmitted through the contacts of sending relay 32 by interrupter 11 and in accordance with which of the relays 1 to 0 of the stock-hundreds register SH is operated. Similarly, relay 16 is operated following the transmission of the stock-hundreds digit and it opens the circuit of relay 32 and closes the circuit of relay 33 so that the next digit is sent out by interrupter 11 through the contacts of sending relay 33.

The remaining sending relays 34, 38, 35, 36, and 37 are operated in the order named under the control of the counting relays of the sender, resulting in the registered stock-units, stock-range, price-tens, price-units, and price-fractions digits being transmitted by the interrupter 11. All of these transmitted digits are, of course, repeated by the repeater R, Fig. 6, in a manner to be explained more fully hereinafter.

Cutting in the other transmitter

In order for the other transmitter to start sending as soon as the operating transmitter has transmitted the last digit, it is necessary for a starting ground potential to be applied to the other transmitter at the same time that the operating sender starts to send out the next to the last digit, as the time of the sending of two digits is required for the first and second counting relays in the other sender to operate before the other sender sends out the first digit. The way this cutting-in of the other transmitter at the proper point is accomplished will now be explained.

When relay 20, Fig. 4, operates, under the control of interrupter 12, following the sending of the price-tens digit, in addition to releasing sending relay 35 and operating the price-units sending relay 36, relay 20 disconnects the grounded conductor 207 from conductor 526, thereby opening the circuit of relay 601, Fig. 6. Relay 601 thereupon falls back and connects conductor 526' to relay 602 of the transmitter T2. If conductor 526' in the transmitter T2 is grounded at this time responsive to a quotation having been set up therein, relay 602 operates and disconnects relay 601, at the same time applying starting ground potential to conductor 525' to start the sender in the transmitter T2 into operation.

Clearing out the register set

Following the transmission of the last digit in the quotation, the remaining counting relays 22 to 27 continue to operate. When counting relay 23 operates, it removes ground potential from the sender branch 208 of the register-locking conductor, thereby removing ground potential from the register locking conductor 210 of register set No. 1. When this occurs, all of the locked-up relays in register set No. 1, including start relay 205 and connecting relay 307, fall back. When start relay 205 falls back it removes the ground potential from outgoing start con-

ductor 207, thereby opening the circuit of the locking magnet 111. Magnet 111 deenergizes and frees the stock-range keys for further operation. The operator is now at liberty to set up the range digit of the next quotation, and thereby fully prepares register set No. 2 for transmission of the next quotation by the sender of Figs. 3 to 5.

Clearing out the sender

As the counting relays 24 to 27 of the sender continue to operate, additional impulses delivered by interrupter 12 are counted, thereby providing the necessary space between the successive quotations transmitted by the transmitter No. 1.

When relay 27 operates through its own normally closed contacts controlled by its right-hand armature and through the contacts of the operated relay 26, responsive to interrupter 12 coming into closed position, it connects its winding directly to the upper brush of the interrupter 12 at its right-hand armature, at the same time disconnecting the upper brush of interrupter 12 from the operating chain circuit extending to the preceding counting relays, and at its left-hand armature it applies a local ground connection to conductor 525 so as to maintain this lower brush of interrupter 12 grounded for the duration of the instant impulse, at the same time removing ground potential from the locking conductor 30 527. When this ground potential is removed, counting relays 13-26 all fall back. Therefore, when relay 21 falls back at the end of the instant impulse being delivered by interrupter 12, the relays 13-27 are all in normal position and 35 are in readiness to be operated again in the hereinbefore described manner in case the incoming start conductor 525 has become grounded again responsive to a second quotation being set up on the No. 2 register set.

Repeating the digit impulses

The first digit, the transmitter-identifying digit, is transmitted by the transmitting interrupter 11, Fig. 5, under the control of relay 31, which is energized momentarily as hereinbefore described. The conductors 521-524, associated with sending relay 31, are brought out to terminals indicated in Fig. 6, and conductors 521-523 are strapped to terminals connected to the conductors A to D leading to the repeater R. By this strapping, the transmitted identifying digit is composed of the characters A, B, and D. It is to be noted that the transmitter-identifying digit transmitted from the transmitter T2 is composed of the characters A, B, C, and D, as all four of the conductors 521'-524' are connected up to the impulse conductors extending to repeater R.

In the repeater R, it is to be noted that the relays A to D are normally in a deenergized condition and that current from the positive line-battery is normally flowing over each of the conductors of each of the lines, such as line 1 and line 2. Now, when the ground impulse constituting the preliminary, transmitter-identifying digit is transmitted over conductors A, B, and C to the A, B, and C relays (605, 606, and 607) each of these relays operates, momentarily shifting the A, B, and C conductors of each outgoing line 70 from the positive line battery to the negative line battery, thereby momentarily reversing the current flow in each outgoing A, B, and C line conductor. When the relays fall back at the end 75

of the digit, the normal current flow over the affected line conductors is resumed.

In a similar way, the stock-code digits 1, 2, and 2, the stock-range digit 3, and the price digits 5 0, 4, and 1 are repeated by relays A to D of the repeater R, the appropriate ones of the repeating relays operating in each case, as determined by the combination of the incoming conductors A to D which are grounded.

10 *Operation of the receiving apparatus*

The digits repeated by the repeater R affect the receiving relays at each receiver in the system. In the receiver shown in Figs. 7 to 13, 13 the concerned ones of the receiving relays 701-704 (A-D), Fig. 7, fall back momentarily responsive to the transmitted digits of the quotation. Since the first digit transmitted, the transmitter—or group-identifying digit, comprises 20 characters A, B, and C, represented by current reversals over line conductors A, B, and C, relays 701-703 all fall back momentarily responsive to this digit. Each of these relays closes a circuit for release relay 730, whereupon relay 730 operates and applies potential to holding conductor 25 723. It is to be noted that the winding of relay 730 is shunted by the associated resistance element. This arrangement permits current to circulate through the winding of relay 730 and the 30 associated resistance element between impulses, thereby rendering the relay slow-releasing, so that it remains operated continuously as long as impulses are continuously received.

35 *Selecting the receiver section*

As explained hereinbefore, each receiver is divided into two sections, each section arranged to handle quotations concerning a separate one 40 of the two groups into which the stocks are divided. Since the instant quotation is one concerned with a stock in group 1, and handled by transmitter T1, the first receiver section is the one to be selected.

When the A, B, and C relays of Fig. 7 fall 45 back in response to the momentary current reversal on line conductors A, B, and C, constituting the transmitter-identifying digit, a circuit is closed through the contacts of the A, B, and C relays 701, 702, and 703, and through the lower 50 armature of the operated D relay, 704, by way of conductor 726 and the upper contacts of relay 710' for relay 709. Relay 709 operates and closes a locking circuit for itself in series with relay 710. This locking circuit includes the now-energized 55 conductor 719, which is a conductor in cable 715. Conductor 719 is grounded because it is connected to the now-energized holding conductor 723, through contacts of relay 909. Relay 710 does not operate for the time being because 60 it is supplied with the same potential at both terminals.

At the same time that relay 709 is operated, relay 711 is operated in multiple with relay 709 and through additional contacts of relay 710. Upon operating, relay 711 closes a locking circuit for itself through transfer relay 801, associated 65 with the stock-hundreds register SH. This locking circuit includes the positively-charged holding conductor 723 and contacts of relay 803. Relay 801, like relay 710, does not operate as long as the initial circuit of relays 709 and 711 remains closed.

When the receiving relays A, B, and C reoperate upon the termination of the transmitter-identifying digit, they open the initial circuit of

relays 701 and 711, whereupon relays 710 and 801 operate in series with relays 701 and 711, respectively. When relay 801 operates, it connects the conductors A to D of the local conductor group 731 to the relays A to D of the stock-hundreds register SH, preparatory to the registration of the stock-hundreds digit. When relay 710 operates, it disconnects conductor 718 from relays 709' and 711' at its lower armature; disconnects conductor 726 from relays 701 and 711 at its inner-lower and middle-lower armatures; and at its upper armature it joins conductors 720 and 721 together, thereby placing a positive potential on conductor 720, as conductor 721 is connected by way of the left-hand armature of relay 907, and the middle right-hand armature of relay 909 to the positively energized holding conductor 721, controlled by relay 733. The placing of a positive potential on conductor 720 results in the energization of connecting relay 901, Fig. 9, to connect up the registers PT, PU, and PF for operation through conductors 808-810; in the energization of relay 1001, Fig. 10, to connect the conductors 1 to 0 controlled by the stock-units register SU to 25 the tens relays of section 1; and in the energization of relay 1201, Fig. 12, to connect the conductors 1 to 0 controlled by the stock-range register SR to the range relays of section 1. By the above-mentioned operation of relays 901, 30 1001, and 1201, section 1 of the receiver has been selected and connected up for operation.

Receiving and storing the quotation digits

When the two impulses are received over conductors A and B of group 731 corresponding to the transmitted hundreds digit 1 of the stock code 122, relays A and B of the stock-hundreds register SH are operated through contacts of the energized relay 801. Upon operating, these 40 relays energize the associated No. 1 conductor, at the same time locking themselves to conductor 811, now energized through the inner contacts of connecting relay 901. At the same time, conductor 722, which is energized upon the 45 falling back of any one of the impulse receiving relays A to D, Fig. 7, is energized by relays A and B, thereby closing a circuit for relay 802, associated with the stock-tens register ST. This circuit includes contacts of relays 907, 905, 50 and 903, contacts of the now-energized connecting relay 901 of section 1, conductor 810, and contacts of relays 807, 805, and 803. When relay 802 operates, it locks itself to the energized holding conductor 723 through relay 803 and through 55 contacts of relay 805. As a result, transfer relay 803 operates when the stock-hundreds digit subsides, connecting up the actuating conductors A-D to the relays A-D of the stock-tens register ST at its right-hand armature. At its inner-left-hand armature, relay 803 shifts the transfer-control circuit from relays 802 and 803 to relays 804 and 805. At its outer left-hand armature, relay 803 disconnects the transfer relay 801, whereupon relay 801 falls back and disconnects the conductors A-D from relays A-D of the stock-hundreds register SH.

When the stock-tens digit 2 is received, relays A and B in the stock-tens register ST are operated through contacts of relay 803, and they 70 lock themselves to the energized locking conductor 811. At the same time, relay 804 is operated through contacts of relay 803, closing a locking circuit for itself through relay 805 and contacts of relay 807. As a result, when the tens digit 75

subsides, transfer relay 805 operates and connects the conductors A—D to the corresponding relays of the stock-units register SU, at the same time transferring the transfer control conductor from relays 804 and 805 to relays 806 and 807, and restoring relays 802 and 803.

In a similar manner, relay 806 is operated from the transfer control conductor 722 through contacts of relay 805 at the same time that relays A and B in the stock-units register SU operate to record the stock-units digit 2, and relay 807 operates at the end of the stock-units digit to prepare for the receipt of the stock-range digit and to restore relays 804 and 805.

At the same time that the stock-range digit 3 is being recorded by relays A and D of the stock-range register SR, relay 902 is operated through contacts of relay 807 and over conductor 809, with the result that relay 903 responds at the end of the stock-range digit and releases relays 806 and 807.

Coincident with the registration of the price-tens digit by the energization of relays A, B, and D in the price-tens register PT, relay 904 is energized; and coincident with the registration of the price-units digit 4 by the energization of relay B, relay 906 is operated through contacts of the operated relay 905 to close a locking circuit for itself in series with relay 907, this locking circuit including the middle armature of relay 909 and the energized locking conductor 723.

When the price-units digit subsides, and the initial circuit of relay 906 is opened, relay 907 operates in series with relay 906 and restores relays 904 and 905, at the same time extending the transfer-control circuit to relay 909. Relay 907, in addition to releasing relays 904 and 905 and its left-hand contacts, removes the holding potential from conductor 721, and consequently from conductor 1120, permitting relays 901, 1001, and 1201 to fall back, as will be discussed more fully hereinafter.

When the price-fractions digit is received, relay D in the price-fractions register PF is operated through contacts of relay 907. In addition to closing the usual locking circuit for itself and connecting up the associated No. 1 conductor, relay D closes a circuit at its right-hand armature for relay 909 in series with resistance element 908. Relay 909, however, does not operate during the price-fractions digit because it is shunted by the potential applied to the junction of its winding and the resistance 908 from conductor 722, by way of the contacts of relay 907.

When the price-fractions digit subsides, relay 909 energizes in series with relay 908 and closes a locking circuit for itself through contacts of relay 906, at the same time disconnecting the energized holding conductor 723 from conductor 719. This opens the locking circuit of relays 906 and 907, and it also opens the locking circuit of relays 709 and 710, Fig. 7. Relays 709 and 710 fall back immediately, as does relay 907, but relay 906 does not fall back for an interval because it is a slow-releasing relay. As long as relay 906 remains operated, it holds the locking circuit closed to relay 909, maintaining relay 909 operated to maintain the locking potential removed from conductor 721 sufficiently long to make it certain that relays 907 and 709 and 710 have fallen back.

As an additional result of the operation of

relay 909 upon the subsidence of the price-fractions digit, conductors 717 and 718 are joined together at the right-hand contacts of relay 709, thereby shunting the lower contacts of relay 710, Fig. 7, so as to extend conductor 718 immediately to relays 709' and 711' in order to render these relays available to respond immediately to a transmitter-identifying impulse from transmitter T2, and over line conductors A—D.

It will now be seen that the receiver is in readiness to receive a stock quotation pertaining to a stock in group 2 and transmitted by transmitter T2 at the central transmitting station.

After a slight interval, slow-acting relay 906, Fig. 9, falls back and opens the locking circuit of relay 909, permitting relay 909 to fall back also. It is to be pointed out that it is not necessary for the slow-acting relay 906 to fall back before the next impulse arrives, as the next impulse is one coming from transmitter T2 to select the No. 2 section of the receiver or else there is a delay before the next impulse arrives equal to the time required to transmit a complete quotation.

Stock selection

25

The way in which the group of indicators corresponding to the stock with which the instant quotation is identified is selected will now be pointed out.

It is assumed that there are approximately twelve hundred stocks being handled by the present stock-quotation system, and that they are about equally distributed between the two transmitters, and consequently between the two receiver sections. As a result, each receiver section must provide for the selection of any one of six hundred stocks, although only a small portion of the total number is ordinarily subscribed to by any one broker.

When the stock-hundreds digit 1 is registered on the stock-hundreds register SH, Fig. 8, wherein relays A and B are operated, positive potential is extended through contacts of relays A and B to the associated digit-1 conductor, closing a circuit for relay H1, Fig. 10. It is to be noted that only six of the ten digit conductors of the stock-hundreds register SH are extended to hundreds relays such as relays H1, H2, and H6, as indicated by the double-bracketed line 812 extending from the stock-hundreds register SH, Fig. 8, across the sheet on which Fig. 9 is drawn to the hundreds relays of Fig. 10. When relay H1 operates, it connects the digit conductors 1-0 represented by the double-bracketed line 813 of the stock-tens register ST, Fig. 8, to the associated tens relays in hundreds group 1, of which the tens relay T12 of section 1 and the corresponding tens relay T'12 of section 2 are shown.

When the stock-tens digit 2 is registered on the stock-tens register ST, Fig. 8, wherein relays A and C are operated, relays A and C place a positive potential on the associated digit-2 conductor, closing a circuit through contacts of relay H1, Fig. 10, for the tens relay T12. Relay T12 thereupon operates and connects the ten units conductors 1-0 to ten corresponding terminals on the section 1 jumper block, 1002, of which terminals 121, 122, and 120 are shown. At the same time, relay T'12 of section 2 is operated in multiple with relay T12, but its operation is of no concern at this time, as the connecting relay 1001' of section 2 is not at this time energized.

When the stock-units digit 2 is registered on the stock-units register SU, Fig. 8, relays A and D connect a positive potential to the associated digit-2 conductor, extending the positive operating potential through contacts of relays 1001 and T12 to terminal 122 on the terminal block 1002 of the intermediate distributing frame IDF. It is assumed that the stock BBA (concerning which the present quotation is being transmitted) is a stock the quotations of which are to be indicated on the auxiliary board and the executive board, in addition to the main board. Accordingly, three jumpers extend from terminal 122 of block 1002, one jumper extending 15 to the terminal in block 1003 of the main board which terminates conductor 1006; another jumper extends to the terminal on block 1004 of the auxiliary board which terminates conductor 1007; and the third jumper extends to 20 the terminal on block 1005 of the executive board which terminates conductor 1008. As a result, stock relays 1301, 1302, and 1303, Fig. 13, located on the main, auxiliary, and executive's boards, respectively, operate over conductors 25 1006-1008 responsive to the potential placed on terminal 122 of block 1002. Upon operating, each relay prepares a locking circuit for itself to the locking conductor 1159, which is energized shortly, upon the operation of start relay 30 1135, as will be pointed out in detail hereinafter.

Selecting the stock range

With relays A and B energized in the stock-range register SR in response to the receipt of the stock-range digit 3, corresponding to the 35 last price in tens, units, and fractions digits the associated digit-3 conductor is connected up through contacts of relays A and D, which are operated, and through contacts of the unoperated relay B. The circuit for energizing the 40 digit-3 conductor of the register SR includes contacts of the transfer relay 806, which is operated prior to the receipt of the stock-range digit and which is released responsive to the 45 receipt of the price-tens digit. By this arrangement, the stock-range register SR is permitted to operate and to become locked before the energizing potential is applied, thereby preventing a momentary energizing potential from being 50 applied to one of the other digit conductors in case one register relay happens to operate slightly more quickly than another.

With the digit-3 conductor associated with the stock-range register SR energized, a circuit is closed through contacts of the section-1 55 connecting relay 1201, Fig. 12, for the last-price (LA) relay 1210. Relay 1210 operates and prepares a locking circuit for itself to conductor 925, controlled by start relay 1135.

Starting the local sender

It will be recalled that transfer relay 904 is operated over the transfer-control conductor 722 at the same time that relays A, B, and D in the price-tens register PT are operated to record 65 the price-tens digit. When relay 904 operates, it places a positive potential at its right-hand armature on start conductor 924, closing a circuit for the upper winding of the differential start relay 1135. When relay 1135 operates, it 70 closes a locking circuit for itself at its inner-upper armature through the associated resistance; places a positive potential on conductor 1159 at its upper armature to lock the operated stock relays (in this case, relays 1301, 1302, 75

and 1303); places a positive potential on locking conductor 925 at its middle upper armature, thereby providing a locking circuit for the range relays 1202-1210 and a locking circuit for any operated ones of the register relays of the 5 price registers of Fig. 9; and at its lower armature, relay 1135 places ground potential on conductor 1171, thereby providing operating and locking circuits for relays 1119-1132 and 1134.

The section-1 local sender now starts operating to restore and reset the selected indicators.

Restoring the selected indicators

With the last price-range relay 1210 operated, and with stock relays 1301-1303 operated, the last price indicators of stock BBA have been selected on the three indicating boards, Fig. 13. The next operation to be performed is the restoration of the selected indicators to blank position, which operation is performed as follows:

When operating potential is placed on conductor 1171 by start relay 1135 as above pointed out, an operating circuit is prepared for pick-up relays 1119 and 1120 by way of the upper contacts of cam 1101. Then, as soon as these contacts close, relay 1119 operates and locks itself to conductor 1171 in series with relay 1120. Relay 1120 does not operate for the time being because it is supplied with the same potential at 30 both terminals. When the upper contacts of cam 1101 separate, however, the initial circuit of relay 1119 is opened, whereupon relay 1120 operates in series with relay 1109 and shifts the upper contacts of cam 1101 from in association with relays 1119 and 1120 into association with relays 1121 and 1122, by way of contacts of relays 1132, 1128, 1126, 1124, and 1122. As a further result of its operation, relay 1120 applies operating potential to conductor 1173 40 which potential is extended through contacts of relay 1134 to the tens, units, and fractions operating conductors 921, 922, and 923. Since conductors 921-923 are connected to conductors 1141-1143, the operating potential is now extended to the upper contacts of each of the cams 1102-1116. These cam contacts, therefore, send impulses over conductors 1144-1158 to the three indicator boards of Fig. 13 by way of contacts of the operated stock-range relay and stock 50 relays. Since only the last-price relay 1210, Fig. 12, is operated, only conductors 1144, 1146, and 1148 of the impulse group pertaining to the main board are connected through, and these are connected through to conductors 1234, 1235, and 55 1236. The impulses transmitted over conductors 1234-1236 pass through contacts of the operated stock relay 1301 to the tens, units, and fractions indicators in the bottom row (LA). As will be explained more in detail hereinafter, ten restoration impulses are transmitted over conductors 1234-1236, which is a sufficient number to advance an indicator from any position to blank position. The indicators cannot advance beyond blank position while the restoring impulses are 65 being transmitted, as the cam springs such as springs 1405 shift the return circuit for the indicator from ground to the normally ungrounded actuating-ground conductor 1304. Accordingly, the last-price indicators of stock BBA, code 122, 70 of the main board MB are restored to blank position. At the same time, the impulses transmitted over conductors 1150, 1152, and 1154, specific to the auxiliary board, pass through contacts of the last-price relay 1210 and by way of 75

conductors 1250-1252 and through contacts of the stock relay 1302 to the last-price indicators of stock BBA on the auxiliary board AB, restoring all of these indicators to blank position. 5 In addition, the ten restoring impulses transmitted over conductors 1156-1158, individual to the executive board, pass through contacts of the last-price range relay 1210, over conductors 1253-1255, and through contacts of stock relay 1303 to the indicators of stock BBA on the executive board EB. These impulses restore these three indicators to blank position.

Operation of indicators

15 The operation of the indicators of Fig. 13 will be described more in detail with reference to Figs. 17 and 18, which show two views of an indicator, assumed to be the last-price fractions indicator of stock BBA on the main board MB, 20 Fig. 13. Each stock indicator comprises essentially an indicating drum, such as the drum 1702; a driving magnet such as the driving magnet 1701; and a ratchet device operated by the magnet to advance the drum one-half step upon 25 the operation of the magnet and the remaining one-half step upon the restoration of the magnet. A front piece 1703 is provided with a window through which the numerals on the drum are exposed, one at a time. The drum 1702 carries 30 also a cam 1704, which has a projection thereon arranged to engage the cam spring 1705 when the indicator is in blank position, and shift the return circuit for the magnet 1701 from its local path to ground into connection with the branch 35 1304 of the actuating-ground conductor 1161. The actuating-ground conductor is not grounded during the transmission of the restoration impulses; and, as a result, each stock indicator being 40 restored, upon arriving in blank position, is unable to move further because its magnet circuit is shifted over to the ungrounded actuating conductor.

As will be hereinafter pointed out, when the 45 resetting impulses are to be transmitted, the actuating ground conductor is connected to ground by the local sender, providing a ground return circuit to advance the indicators from blank position.

Counting the restoration impulses

The way in which the restoration impulses are counted by the operation of relays 1 to 8, 9', and 0' (1121-1128, 1131, and 1132) will now be pointed out. It is to be noted that the upper contacts of cam 1101 become closed just as the remaining cams 1102-1116 are opening the upper sending contacts, that the contacts of cam 1101 are again opened just as the cams 1102-1116 are 50 again opening their upper contacts, and that an impulse is sent, therefore, over each of the conductors 1144-1158 during each closed portion of the upper contacts of cam 1101, as well as during each open portion of the cam. As a result, each 55 of the cams 1102-1116 transmits twice as many impulses as the cam 1101, and ten restoring impulses are transmitted by the cams 1102-1116 by the time five impulses have been transmitted to the counting relays of the local sender, following the operation of relay 1120 at the termination of the pick-up impulse. Relays 1121, 1123, 1125, 1127, and 1131 operate responsive to the beginning of the first, second, third, and fourth impulses from cam 1101, respectively, and

the relays 1122, 1124, 1126, 1128, and 1132 operate at the end of the first, second, third, fourth, and fifth impulses, respectively. The relays 1121-1128 are locked to conductor 1172, which is connected to locking conductor 1171 through contacts of relay 1131. Now, when relay 1131 operates at the beginning of the fifth impulse delivered by the upper contact of cam 1101 following the operation of pick-up relays 1119 and 1120, it locks itself to the incoming impulse conductor controlled by the upper contacts of cam 1101 and over a circuit path which is independent of the contacts of relays 1128, at the same time opening the connection between the armature of relay 1128 and the impulse conductors. At its lower armature, relay 1131 locks itself to conductor 1171 in series with relay 1132, at the same time disconnecting conductor 1172 from conductor 1171. When this occurs, relays 1121-1128 all fall back, preparatory to being 10 reoperated to count the resetting impulses.

At the termination of the impulse which operates relay 1131, relay 1132 operates in series with relay 1131 and again places locking potential on conductor 1172 by means of its lower contacts; 25 at its inner-upper armature it prepares to operate relay 1129 instead of relay 1131 upon the second operation of the counting chain; and at its upper armature it disconnects the impulse conductor from the junction of its own winding 30 and that of relay 1131, at the same time extending it through contacts of relays 1128, 1126, and 1124 to relays 1121 and 1122 again.

By this time, ten restoration impulses have 35 been transmitted to the selected indicators over the paths pointed out, restoring them all to blank position.

Resetting the restored indicators

The way in which the restored indicators are 40 reset to the respective position designated by the digits registered on the price registers (PT, PU, and PF) of Fig. 9 will now be explained. Upon referring again to the section 1 local sender of Fig. 11, it will be noted that the actuating- 45 ground relay 1134 is operated in multiple with relay 1132, when relay 1132 operates at the end of the tenth restoring impulse. It is to be noted that the resistance element 1133 is shunted around relay 1131, thereby furnishing additional 50 current for operating relay 1134 in multiple with relay 1132. At its three upper armatures, relay 1134 disconnects the tens, units, and fractions conductors 921, 922, and 923 from the conductor 1173, energized at the upper contacts of 55 pick-up relay 1120. By this arrangement, the current-supply for the impulse-sending contacts of the impulse machine IM is restricted to the digit conductors 1 to 0 controlled by the upper contacts of relays 1121-1130 and multiplied to the bases of the contact pyramids of the price registers of Fig. 9. At its three lower armatures, relay 1134 places actuating ground potential on conductors 1161-1163, extending to 60 the main, auxiliary, and executive boards, respectively. The placing of ground potential on these conductors provides a ground return circuit for the last-price indicators of Fig. 13, which have been shifted into connection with branch conductors 1304, 1305, and 1306', 70 branches of conductors 1161, 1162, and 1163, respectively.

Following the transmission of the ten restoration impulses, the resetting impulses are started without any pause between the two groups other 75

than the regular inter-impulse time interval, as determined by the shape of the sending cams and the speed of the driving motor 1117. The first resetting impulse is transmitted following the operation of relay 1132 and preceding the reoperation of relay 1121. Accordingly, since the reoperation of the relays of the counting chain proceeds as explained in connection with the first operation of the relays, the counting relays 11 to 0 operate immediately following the transmission of the first to tenth restoration impulses, respectively. It will be understood, of course, that relays 1129 and 1130 (9 and 0) count the ninth and tenth resetting impulses, whereas the ninth and tenth restoration impulses were counted by relays 1131 and 1132.

With the digit 0 set up on the price-tens register PT, wherein registers A, B, and D are operated, the energizing potential placed on conductor 1173 through the upper contacts of pick-up relay 1120 is extended through the upper contacts of relay 1130 to the digit-0 conductor, and thence by way of the contacts of the operated relays A, B, and D of the price-tens register PT to conductor 921; with the digit 4 set up on the price-units register PU, the energizing potential on conductor 1173 is extended through the upper contacts of relay 1124 to the digit-4 conductor, and thence by way of contacts of the price-units register PU to conductor 922; and, with the digit 1 set up on the price-fractions register PF, wherein relay D is operated, the energizing potential on conductor 1173 is extended by way of the digit-1 conductor and through contacts of the price-fractions register PF to the units conductor 923. In this way, the energizing potential is supplied to the tens, units, and fractions conductors 921, 922, and 923 and is extended, through the tens, units, and fractions conductors 1141, 1142, and 1143 to the upper contacts of the sending cams 1102-1116, enabling the concerned ones of these sending contacts to transmit the resetting impulses to the restored indicators.

45 Terminating the fractions digit 1

When relay 1121 operates, following the transmission of the first resetting impulse, it disconnects the energizing potential from the digit-1 conductor, and consequently from the conductor 923, connected to the apex of the price-fractions register PF, wherein the digit 1 is set up. With the potential disconnected from conductor 923, no potential exists on the supply conductor 1143, and the further operation of the fractions cams 1106 and 1107, 1112 and 1113, and 1116 is ineffective to transmit further fractions impulses. The connected fractions indicators are, therefore, left standing with the digit 1 displayed.

Terminating the units digit 4

When the fourth counting relay, 1124, operates following the transmission of the fourth resetting impulse to the indicators, it disconnects the energized conductor 1173 from the fourth digit conductor, thereby disconnecting energizing potential from conductor 922, connected to the apex of the contact pyramid of the price-units register PU, wherein the digit 4 is set up. Disconnecting the energizing potential from conductor 922 removes the energizing potential from conductor 1142, associated with the upper contacts of the units sending cams 1104 and 1105, 1110 and 1111, and 1115. Therefore, no further

units impulses are transmitted, and the connected units indicators are left standing with the digit 4 exposed.

Terminating the price-tens digit 0

When the tenth counting relay, 1130, operates following the transmission of the tenth resetting impulse, it removes energizing potential from the digit-0 conductor, thereby removing energizing potential from conductor 921, connected to the apex of the contact pyramid of the price-tens register PT, wherein the digit 0 is set up. By this operation, energizing potential is removed from the upper sending contacts of the tens cams 1102 and 1103, 1108 and 1109, and 1114. The connected tens indicators are, therefore, left standing with the digit 0 exposed.

In the foregoing manner, the price digits 0, 4, and 1 have been set up on the last-price indicators shown in Fig. 13.

When relay 1134 operates, all of the resetting impulses have been retransmitted, and the apparatus comprising section 1 of the receiver may be cleared out in a manner to be explained hereinafter.

Clearing out the common apparatus of the receiver

It has been explained hereinbefore how the transfer relays 111, 801-807, and 902-907 are automatically restored, a pair at a time, as the digits of a quotation are received. The register relays of Fig. 8, however, remain locked up to conductor 811, energized through the inner-upper contacts of connecting relay 901, until relay 907 operates at the end of the registration of the price-units digit on the price-units register PU, at which time ground potential is removed from conductor 721, and consequently from conductor 720. By this time, the stock selection has been made, and the appropriate stock-range relay has been energized and locked, as hereinbefore pointed out. As a result, the stock registers and stock-range registers are no longer needed for the instant quotation, and they may be cleared out preparatory to receiving the following quotation. When relays 901, 1001, and 1301 fall back responsive to the above-mentioned removal of energizing potential from conductor 720, relay 901 removes energizing potential from conductor 811, whereupon the locked-up register relays of Fig. 8 fall back.

Clearing out section No. 1

When the tenth counting relay, 1130, of the section-1 local sender, Fig. 11, operates, following the transmission to the indicators of the tenth resetting impulse, it closes a circuit at its inner armature for the lower winding of the differential start relay 1135. The lower winding of the relay now energizes, overpowering the holding effect of the upper winding, which is now locked operated through the associated resistance element. As a result, relay 1135 restores and opens the circuit of both windings at its inner-upper and inner-lower armatures. At its lower armature, relay 1135 removes energizing potential from conductor 1171, stopping the transmission of impulses and permitting the locked-up relays of the local sender to restore; at its upper armature, relay 1135 removes the energizing potential from conductor 1159, thereby opening the locking circuit of the stock relays 1301, 1302, and 1303, whereupon these relays fall back; and at its inner-upper armature, relay 75

1135 removes the energizing potential from locking conductor 925, thereby restoring the locked-up register relays of Fig. 9 and restoring the locked-up range relay 1213 of Fig. 12.

5 Section 1 of the receiver is now completely cleared out, in readiness to handle another quotation from the transmitter T1.

Receiving a quotation from transmitter T2

10 Upon referring to Fig. 6, it will be noted that the transmitter-identifying digit sent out as the first digit of a quotation by the transmitter T2 comprises characters A, B, C, and D, as all four conductors 521'-524' are cross-connected to the outgoing conductors A to D. When this digit is repeated by the repeater R, all four receiving relays 701-704, Fig. 7, fall back, closing a circuit over conductor 718 and through contacts of relay 710 for relays 709' and 711' in parallel, through contacts of relay 719'. Relay 709' locks itself energized in series with relay 710' to conductor 719', corresponding to conductor 719 of section 1. Relay 711' locks itself energized in series with relay 801. As a result, when the transmitter-identifying digit subsides, and relays 701-704 again operate, relays 710' and 801 energize in series with relays 709' and 711', respectively. Relay 801 connects up relays A to D of the stock-hundreds register SH, as in the previously-described operation, wherein it is operated in series with relay 711. Relay 710 at its two lower armatures opens the connection between conductor 718 and relays 709' and 711'; disconnects conductor 726 from relays 709-711 at its upper armature; and at its inner-upper armature it joins conductors 720' and 721' together, thereby bringing about the energization of the connecting relays in section 2 corresponding to connecting relays 901, 1001, and 1201 of section 1.

20 Following this, the stock and range digits are recorded on the registers of Fig. 8 in the manner hereinbefore explained, following which the price digits are recorded on the price registers of section 2, and corresponding to the price registers of section 1, Fig. 9.

Following the registration of the price-units digit in section 1, the relay therein corresponding to relay 907 of section 1 removes potential from conductor 721', deenergizing the connecting relays specific to section 2, which results in the release of the registers of Fig. 8 responsive to the removal of potential from conductor 811 by the section 2 relay corresponding to relay 901 of section 1.

55 Following the registration of the price-fractions digit in section 2, the relay therein corresponding to relay 909, Fig. 9, operates, removing ground potential from conductor 719' to release relays 709' and 710', in addition to immediately joining conductor 717' and 718' together in order to provide an immediate operating circuit for relays 709 and 711 in case the first digit, the transmitter-identifying digit, of the next quotation follows immediately.

65 Upon referring to Fig. 10, it is to be noted that relay 1001' is operated over conductor 720' when section 2 is receiving a quotation. With relay 1001' operated, the digit conductors associated with the stock-units register SU, Fig. 8, are connected to stock-tens selecting relays of section 2, including relays T'12, T'21, and T'60, instead of to the contacts of the corresponding relays of section 1. In this way, the terminals of terminal block 1002' of section 2 are rendered

effective to operate stock relays, instead of the terminals of block 1002 of section 1.

Setting up short quotations

In the quotation hereinbefore considered, the 5 tens, units, and fractions digits were transmitted. It will be understood, of course, that the tens digit of a new quotation of a given stock is rarely different from the tens digit of the preceding quotation, for which reason it is 10 rarely necessary to change the setting of the tens indicator. It is unnecessary for the operator to ascertain and set up the tens digit of the quotation when it is the same as the tens digit of the previously-transmitted quotation 15 of the same stock. Moreover, it is the regular practice for the units and fractions digits only of a stock quotation to be delivered to the transmitting station from the stock exchange when the tens digit is the same as that of the 20 preceding quotation. Accordingly, the operator is provided with two range keys instead of one for each of a plurality of the stock ranges and stock-range combinations, one key for a quotation containing units and fractions digits, and 25 another key for a quotation containing tens, units, and fractions digits. In each case, the letters in parentheses under the regular designation of a range key, Fig. 1, indicate the number and the denomination of price digits which will 30 be effective when the key is depressed. To illustrate, let it be supposed that a new quotation is to be set up for stock BBA, and that the tens digit is the digit 0 as in the preceding 35 quotation, but the units and fractions digits are now 3 and 7, respectively. In this case, the complete quotation, as set up by the operator, is BBA—(BL)37—LA(UF), and is called a short quotation.

The setting up of the stock letters B, B, and 40 A results in the stock-code digits 1, 2, and 2 being set up on the registers SH, ST, and SU, Figs. 5 and 4, in the hereinbefore described manner. In order to cause the units and fractions digits to be sent through as digits of the 45 desired denomination, the operator depresses the digit-blank key BL, Fig. 1, to set up the digit blank on the price-tens register PT, Fig. 4, wherein the relay A is operated, in accordance with the price-digit code table of Fig. 21. The 50 operator next actuates her price-digit keys 3 and 7 in succession, setting up the units and fractions digits 3 and 7 on the registers PU and PF of Fig. 3. Following this, the operator operates the stock-range key LA(UF), setting 55 up the stock-range digit, the price-range and digit 0 on the stock-range register SR, Fig. 3, in accordance with the code table of Fig. 20, wherein the digits 3 and 0 are represented by the characters A, C, and D, corresponding to 60 the last price in units and fractions digits. In the receiver of Figs. 7 to 13, the registering apparatus of Figs. 8 and 9 is operated by the transmitter T1 to set up the same digits as described in connection with the previous connection, except that the digits 3 and 0 are set up in the stock-range register SR by the energization of relays A, C, and D (instead of relays A and D as before); the digit blank is set up in the price tens register PT; and the digits 3 70 and 7 are set up in the registers PU and PF, respectively.

With relay C of the stock-range register SR operated, in addition to relays A and D, an energizing potential is placed on the associated 75

digit—0 conductor through contacts of relays A and C, in addition to an energizing potential being placed on the digit—3 conductor through the contacts of relays A and D. As a result, 5. price-range relay 1118, Fig. 11, connected to the digit—0 conductor of the stock-range register SR through contacts of relay 201, is operated in addition to the stock-range relay 1210. When relay 1118 operates, it prepares a locking circuit 10 for itself at its lower armature, which is closed when energizing potential is placed on conductor 1171 by start relay 1135, and at its upper armature it disconnects the tens conductor 1141 from the conductor 921, thereby 15 preventing any tens impulses from being transmitted in the present quotation.

It may be pointed out that any other digit may be set up on the stock-tens register in the transmitter instead of the digit blank, 20 when only the units and fractions indicators are to be reset, as relay 1118 prevents the transmission of any tens impulses, regardless of the setting of the price-tens register. It is believed, however, that it is more convenient for the operator to remember to operate the digit-blank key 25 under the stated circumstances.

Setting up the previous closing price

At the close of the day, the quotations set up 30 on the stock indicators at the indicator boards are wiped out, and the last price of the day for each stock is set up as the previous closing price, so that it will be shown on the indicating boards when business is resumed on the next business 35 day.

In order to set up the tens, units, and fractions digits of the closing price, as indicated by the last price indicators, of the tens, units, and fractions indicators of the previous closed group, 40 the operator sets up the desired stock-letter combination, the letters B, B, and A for example, following which she sets up the tens, units, and fractions digits on the registers PT, PU, and PF, Figs. 3 and 4, by manipulating the 45 price-digit keys of Fig. 1, following which the operator depresses the key PC(TUF) to predetermine that the price-digits set up will be transmitted as the tens, units, and fractions digits of the previous closing price. Depressing this key 50 results in the operation of relays C and D in the stock-range register SR, setting up the stock-range digit 8, as may be seen in Fig. 20.

In the receiver of Figs. 7 to 13, the quotation is set up in the hereinbefore described manner, 55 section 1 being effective to receive the tens, units, and fractions price digits. In the stock-range register SR, Fig. 8, the operation of relays C and D renders the associated digit—8 conductor effective to close a circuit through contacts of connecting relay 1201 for the previous-close (PC) range relay 1206. When this relay operates, it connects up the conductors extending to the tens, units, and fractions registers in the previous-close group, resulting in the restoration 60 and resetting impulses being transmitted to these registers to set up the tens, units, and fractions digits of the previous closing price.

In case the hundreds digit of the previous closing price differs from the hundreds digit 70 already set up on the hundreds indicator of the previous-close indicator group, or row, the operator must send the new hundreds digit as a separate quotation. In order to do this, the operator sets up the stock letters as before, following 75 which she depresses the concerned one

of the price-digit keys of Fig. 1 to set up the new hundreds digit on the price-tens register PT, Fig. 4. Following this, the operator sets up an arbitrary digit on each of the registers PU and PF of Fig. 3 (the digit blank for example), and she then depresses the previous-close hundreds key, PC(H), thereby operating relay B of the stock-range register SR, Fig. 3, setting up the digit 7 therein, in accordance with the code table of Fig. 20.

In the receiver of Figs. 7 to 13, the quotation digits are received as before, resulting in the appropriate stock being selected in the hereinbefore described manner. In the stock-range register SR, Fig. 8, the energization of relay B 15 results in the associated digit 7 conductor being rendered effective, operating the previous-close hundreds relay 1205 by way of contacts of relay 1201. When relay 1205 operates, it connects up only the hundreds indicator of the selected 20 stock group, resulting in the hundreds indicator of the group PC on the main board MB and the auxiliary board AB being set in accordance with the digit now set up on the price-tens register PT, Fig. 9. The tens, units, and fractions registers of the previous-close group are not affected, as they are not connected up by relay 25 1205.

In this way, the register PT of Fig. 9 is made to serve as the hundreds register, or as a tens 30 register, depending upon the setting of the register SR, Fig. 8.

Clearing out the open, high, low, and last prices

In order to clear out the open, high, low, and 35 last prices for any given stock, stock BBA for example, the operator follows the setting up of the stock letters by setting up the digit blank on each of the registers PT, PU, and PF, Figs. 3 and 4, following which she operates the unison key, UN(TUF), thereby operating relay C in the stock-range register SR, Fig. 3. Operating relay C sets up the digit 9, in accordance with the code table of Fig. 20.

In the receiver of Figs. 7 to 13, this quotation 40 is received in the hereinbefore described manner. In the registers PT, PU, and PF, the receipt of the price-digit blank results in the operation of relay A, in accordance with the code table given in Fig. 21. With relay A alone operated in each of the registers PT, PU, and PF, the apex conductors 921, 922, and 923 are all maintained disconnected from the digit conductors 1 to 0, thereby preventing the transmission of any resetting impulses to the tens, units, and fractions indicators in the selected stock 45 group and stock-range groups.

The operation of relay C in the stock-range register SR results in the associated digit 9 conductor being energized, closing a circuit through contacts of relay 1201 for the unison relay 1204. 50 Relay 1204 prepares the usual locking circuit for itself at its inner-upper armature, at the same time closing circuits for the open, high, low, and last range relays 1207, 1208, 1209, and 1210. Relays 1207-1210 are accordingly operated to 55 connect up the tens, units, and fractions conductors 1226-1236 and 1241-1252, extending to the tens, units, and fractions indicators in ranges open, high, low, and last of the selected stock on the main board MB and the auxiliary board AB. The last-price relay 1210 also connects up the tens, units, and fractions conductors 1253-1255 60 extending to the last-price indicators of the executive board AB.

With the stock-range relays 1207-1210 operated, and with the above-mentioned conductors connected up, the series of restoration impulses is transmitted to all indicators of the selected stock groups, with the exception of the indicators in the top row on the main and auxiliary boards, restoring the open, high, low, and last indicators to blank position. Now, since conductors 921-923 are not connected in the registers PT, PU, and PF, as above pointed out, no resetting impulses are transmitted when the section-local sender goes through its resetting-impulse counting operation, and the above-mentioned indicators are left standing in blank position.

The foregoing operation of setting up the last price of the day as previous-closing price and of then restoring the open, high, low, and last indicators is repeated for each of the stock, thereby preparing the indicator boards for the opening of the next business day.

First quotation of the day; open, high, low, and last

When the first quotation of the day is to be set up for any stock, it is to be set up as the opening price, as the high price, as the low price, and as the last price. As a result, the operator sets up the stock letters and the tens, units, and fractions price digits in the usual way, following which she operates the unison stock-range key UN(TUF), causing the unison range digit 9 to be set up on the stock-range register SR of Fig. 3.

In the receiver of Figs. 7 to 13, the receipt of the unison stock-range digit 9 on the stock-range register SR results in the energization of the unison relay 1204, causing relays 1207-1210 to operate as hereinbefore described to connect up the open, high, low, and last indicators. As a result, the price digits set up on the registers PT, PU, and PF of Fig. 9 are transmitted to these indicators, setting up the first received price for the stock in question as the open, high, low, and last price.

Low-last quotation

In case a subsequent quotation is the lowest so far received for a particular stock, it should be set up as the low price, in addition to being set up as the last price. In order to bring this about, the operator depresses the low-last stock-range key LO-LA(TUF) or the key LO-LA(UF), depending upon whether the quotation contains a new tens digit or not. In one case, the low-last digit 1 is set up alone, while in the other case the digits 1 and 0 are both set up by the depression of the stock-range key, as may be seen upon observing Fig. 20.

In the receiver, the relays A, B, and D, or relays A-D, as the case may be, of the stock-range register SR are operated to set up the digit 1 or the digits 1 and 0. In response to the digit 1 being set up on the stock-range register SR, the low-last range relay 1202 is operated to close circuits for the low and last range relays 1209 and 1210. These two relays are operated to connect up conductors 1231-1236 and 1247-1255, to cause the digits set up on the registers of Fig. 9 to be transmitted to the low- and last-price indicators of Fig. 13.

In case the digit 0 is not set up, relay 1118 is not operated, and the tens indicators in the affected range group are restored and reset, along with the units and fractions indicators. On the

other hand, if the digit 0 is set up along with the digit 1, owing to relay C of the stock-range register ST being operated, relay 1118 of Fig. 7 is operated to prevent the restoration and resetting of the tens indicators.

5

High-last quotations

When the price digits of a quotation are to be set up as the high price of the day, in addition to the last price, the appropriate one of the two range keys, HI-LA(UF) and HI-LA(TUF), is depressed, resulting in the digits 2 and 0, or in the digit 2, being transmitted to the stock-range register SR, Fig. 8, operating the high-last relay 1203, or relay 1203 and relay 1118. Relay 1203 15 operates the high-price relay 1208 and the last-price relay 1210, causing the quotation to be set up as the high price and as the last price.

Other quotations

It will be observed moreover that a pair of range keys is provided for the low price alone, and another pair of range keys is provided for the high price alone, enabling a quotation to be sent when desired as the high price or as the low price, in units and fractions or in tens, units, and fractions, operating either of the relays 1208 or 1209, either alone or in conjunction with relay 1118.

Additional explanation of the transmitters

Referring again to Figs. 1 to 6, additional explanation will be given of the action and interaction of the transmitters T1 and T2. Since both transmitters use the same transmitting line, the most satisfactory arrangement is considered to be one which permits the two transmitters to use the line alternately when both operators are setting up quotations continuously. Under this arrangement each transmitter is barred from starting a second quotation until the other transmitter has completed sending a quotation, if one is set up therein. Ordinarily then, the local sender in a given section of the receiver handles half the quotations sent over the common line, and the corresponding section of the receiver does not receive a second quotation until the time required for the transmission of the quotation to the other section has elapsed. It is obvious that the local senders of a receiver operate more reliably at a relatively low speed than at a higher speed, more time existing for each transmitted impulse. That being the case, the operating speed of the local senders is regulated so that the local sender can transmit a series of restoration impulses and a series of resetting impulses and clear out before the next quotation to the same receiver section has proceeded far enough to cause the circuit for starting the local sender to transmit the new quotation to be closed.

It will be apparent that the greatest line efficiency, consistent with reliable impulsing, is secured when the first digit of a succeeding quotation is transmitted immediately following the last digit of a preceding quotation, and it will be evident that a transmitter must not be permitted to start to send a second quotation any sooner when the alternate transmitter does not transmit a quotation than when it does, keeping in mind the above-mentioned timing of the local senders in the receivers. The way in which the transmitters act and interact to secure the foregoing results will now be particularly explained.

75

It will be recalled that relay 13 of the sender of transmitter T1 responds to a closure of interrupter 12 to close a locking circuit through relay 14 so as to secure an operation of relay 14 when interrupter 12 opens. It will be recalled also that the first quotation digit is transmitted responsive to the operation of relay 14 and through the contacts of the sending interrupter 11. It will be recalled also that the second digit of the quotation is transmitted by interrupter 11 responsive to the operation of relay 15, and that the third, fourth, fifth, sixth, seventh, and eighth digits of the quotation are transmitted responsive to the operation of relays 16, 17, 18, 19, 20, and 21, respectively. It is apparent, therefore, that each of the relays 14 to 21 becomes operated just prior to the transmission of the first to eighth quotation digits, respectively. This fact is denoted in the drawings by the numerals 1 to 8 placed under the relays 14 to 21, respectively, and enclosed in small circles. As will be apparent shortly, the small numbered circles placed under the spacing relays 22 to 27 and relay 13 indicate that relays 22 to 27 operate just prior to the transmission of the first to sixth digits, respectively, by transmitter T2; that relay 27 releases just prior to the transmission of the seventh digit by the other transmitter, and that relay 13 of the sender re-operates just prior to the transmission of the eighth quotation digit by transmitter T2. That being the case, the first digit of the second quotation transmitted by the transmitter T1 follows the re-operation of relay 14, and, therefore, follows immediately after the transmission of the last digit of a quotation transmitted by the transmitter T2, which follows the re-operation of relay 13. With this arrangement, the transmitter T1 cannot transmit the first digit of a second quotation until the sender has counted a sufficient number of impulses to enable the transmitter T2 to transmit a complete quotation.

It will be recalled that the circuit of the lock-out relay 601 associated with the transmitter T1 is opened at the right-hand contacts of relay 20 just prior to the transmission of the seventh digit of the quotation. This operation of relay 20 occurs upon interrupter 12 (and the corresponding interrupter in transmitter T2) coming into open position. As soon as relay 601 falls back, it connects the outgoing start conductor 526' of the transmitter T2 to the lock-out relay 602, permitting relay 602 to operate and connect a ground potential to the incoming start conductor 525' of the transmitter T2 and disconnect relay 601 in time for the relay in transmitter T2 corresponding to relay 13 of the transmitter T1 to operate upon the next closure of interrupter 12 and corresponding interrupter of transmitter T2. The operation, therefore, of the first #8 relay in the transmitter T2 (corresponding to relay 13 of the transmitter T1) takes place at the same time that relay 21 of the transmitter T1 operates following the transmission of the seventh quotation digit and just preceding the transmission of the eighth quotation digit.

When the interrupter 12, together with the corresponding interrupter of the transmitter T2, opens again, relay 22 operates in the transmitter T1, following the transmission of the eighth quotation digit from the transmitter T1, and it cuts off the eighth sending relay 31. At the same time, the relay in transmitter T2 corresponding

to relay 14 in the transmitter T1 operates to connect up the first sending relay, corresponding to relay 31 in the transmitter T1, so that the first quotation digit is transmitted from the transmitter T2 by the interrupter therein corresponding to interrupter 11 of the transmitter T1, before the interrupter 12 together with the corresponding interrupter in the transmitter T2 has changed to a new position. In this way, the impulse counting relays in the transmitter T1 proceed to count the digits transmitted by the transmitter T2 until relay 27 operates just preceding the transmission of the sixth quotation digit by transmitter T2 (releasing the relays 13 to 26), and releases just preceding the transmission of the seventh quotation digit by the transmitter T2. At the same time that relay 27 releases in transmitter T1, the relay in the transmitter T2 corresponding to relay 20 in the transmitter T1 operates to open the circuit of lockout relay 602 of the transmitter T2 and permit relay 601 to operate over conductor 526 and place a ground potential on the incoming start conductor 525 of the transmitter T1, subject to the operator at the transmitter T1 having set up a new quotation and thereby caused conductor 207 to become grounded at start relay 205, or at the corresponding start relay in register set No. 2.

Keeping the receivers in synchronism with the transmitters

As explained hereinbefore, the transfer relays in the receivers are so arranged that they operate automatically to route each digit to the register of the corresponding denomination, and to function properly when no space is provided between successive quotations for releasing the slow-acting holding relays, such as relay 730, Fig. 7, of the receiver of Figs. 7 to 13. It may happen occasionally, however, (because of momentary current failure or because of physical interference with the operation of the transfer relays) that the transfer relays of the receiver get out of step with the sending relays of the transmitter, thereby causing quotation digits to be transmitted to registers of the wrong denomination. Two provisions are contained in the present system for re-synchronizing the transmitters and the receivers. The first provision includes the shunted slow-acting relay 730, Fig. 7, which is controlled by any one of the impulse-receiving relays 701-704 to maintain ground potential on the locking conductor 723 as long as impulses are being received, and to restore and permit any operated transfer relays and associated relays to release in case the impulses stop coming in for a short interval. These no-impulse intervals occur regularly in ordinary operation; as, invariably, an operator will fail occasionally to have a complete quotation set up on her transmitter when the other transmitter has finished sending a quotation. If desired, special arrangements could be employed for introducing a delay in sending at regular intervals. This, however, is thought to be unnecessary because of the above-mentioned intervals which regularly take place naturally in the operation of the system.

The second provision for restoring the synchronism between a receiver and the transmitter involves the arrangement for operating the relays 709 and 711 of receiver section 1 and the corresponding relays 709' and 711' of receiver section 2. In case the receiver of Figs. 7 to 13 gets out of step with the transmitter, for example when a quotation is being received by receiver section 1, 75

the last digit of the instant quotation does not result in the transfer chain, including relays 801-807 and 902-907 being completely operated. As a result, the beginning of the following quotation results in additional transfer relays and associated digit registers being operated, which operation continues until relay 909 operates upon the termination of the digit transmitted to the price-fractions register PF. At this time, relays 709 and 710 are released, and relays 901, 906, and 909 fall back. None of the transfer relays 801-807 can operate, following this, until relays 709' and 711' or relays 709 and 711 have operated. It requires the simultaneous deenergization of relays A, B, and C to operate relays 709 and 711, and it requires the simultaneous deenergization of receiving relays A to D to operate relays 709' and 711'. Regular quotations rarely contain either of the character combinations A, B, and 20 C and A, B, C, and D, as may be seen from inspection of Figs. 19, 20, and 21, which give the character combinations for the various digits to be transmitted. That being the case, the transfer relays of the receiver ordinarily remain in normal condition until a transmitter-identifying digit is received at the starting of a new quotation, operating either relays 709 and 711, or relays 709' and 711', to prepare the transfer relays for operation.

30 Stopping the Motor generators at the receivers

Referring now particularly to Figs. 6 and 7, the arrangement for stopping the motor generators at the receivers will be pointed out:

35 After the operators have finished transmitting quotations at the close of the business day, an attendant depresses the push-button 609, following which he opens the switch 604. Depressing the push-button 609 results in the reversal of line current over all conductors on each transmission line. In the receiver shown in Figs. 7 to 13, relays A to D all fall back when the line current is reversed in all conductors, and relays A and D open the circuit of slow-acting relay 40 705 at their inner-lower armatures, while relays B and C open points in the preliminary start circuit of the motor generator MG at their lower armatures. Relay 705 is rendered slow acting so that it remains operated continuously during the regular operation of the system and does not fall back while impulses are being transmitted, but it now falls back responsive to a prolonged opening of its circuit at relays A and B. Upon falling back, relay 705 opens the circuit of relay 706, and relay 706 falls back and opens the circuit of the relay in the starter S, which relay falls back and opens the motor generator circuit. The motor generator is, therefore, stopped; and the bus-bars 707 and 708 are deenergized. This automatically stops the impulse machine IM.

When the switch 604 is opened, the push-button 609 can be released, as the deenergization of relays A to D of the repeater does not now restore the normal line current, and the receiving relays A to D, Fig. 7, remain restored.

Starting the motor generators at the receivers

In order to start the motor generators at the receivers, it is merely necessary to close the switch 604, thereby restoring the normal flow of line current over each conductor of all the transmission lines. When this occurs, the receiving relays A to D, Fig. 7, all operate responsive to the flowing line current. Relays A and

D prepare a circuit for relay 705, which is effective as soon as bus-bars 707 and 708 become energized, and relays B and C close a circuit through contacts of relay 706 for the starter S of the motor generator MG. The starter S thereupon operates and starts the motor generator MG into operation. Relay 706 is operated through contacts of relay 705 as soon as bus-bars 707 and 708 become energized, thereupon closing a local circuit for the starter S of the motor generator MG, which excludes the contacts on relays B and C, disconnecting the commercial power circuit from the contacts of these relays.

15

Operation of the modified receiver

Referring now to the drawings as assembled in Fig. 23, which differs from Fig. 22 in that Figs. 7, 8, and 9 are replaced by Figs. 14, 15, and 16, respectively, the operation of the modified receiver will now be explained.

It may be pointed out that one feature of the modified receiver is that the entire transfer chain of relays is common to both receiver sections in the modification, whereas in the embodiment previously described the chain of transfer relays has two branches, one for each receiver section (the branch for section 1 including relays 902-907 and 907).

Another feature of the modified receiver is 30 that a group of impulse-distributing relays (1403-1405) has been inserted between the transfer control conductor M-722 and the transfer counting chain, resulting in the number of relays in the transfer counting chain being halved; and a further feature of the modified receiver is that the relays for selecting the receiver sections responsive to the transmitter-identifying digit has been reduced to two, with an accompanying simplification of the circuit 40 arrangement.

In Figs. 14-16, it is to be noted that certain reference characters have the letter M as a prefix. The letter M distinguishes such reference characters from the reference characters applied in Figs. 7-9 to similar conductors and pieces of apparatus.

It is to be noted that the motor generator MG and associated apparatus is not reproduced on Fig. 14, but it will be understood that the same 50 motor generator and its associated apparatus is employed as is disclosed in Fig. 7.

In order to explain the operation of the modified receiver, it will now be assumed that a quotation is received, a quotation from the transmitter T for example. When the transmitter-identifying digit of the quotation arrives, relays A, B, and C of Fig. 14 respond to the current reversal in the associated conductors, closing a circuit for the slow-releasing holding relay 55 M-730. Relay M-730 thereupon operates and places an energizing potential on the locking, or holding, conductor M-723. At the same time, the A, B, and C relays (M-701', M-702', and M-703') close a circuit through contacts of the operated relay M-704' for the section 1 selecting relay 1401. Relay 1401 thereupon operates and locks itself to conductor 1406, now energized by virtue of its connection with the energized holding conductor M-723 by way of contacts of release relay 1608, Fig. 16. Relay 1401 also opens its initial energizing circuit at its inner armature, and at its lower armature it places an energizing potential on conductor 720, 75

thereby operating the section—1 connecting relays 1601, 1001, and 1201.

As a further result of the momentary restoration of the A, B, and C receiving relays of Fig. 14, a momentary impulse is transmitted over the transfer-control conductor M—722 by way of contacts of relay 1404 to conductor 1401. Relay 1405, being connected to conductor 1407, operates and closes a locking circuit for itself through the upper winding of relay 1404, which locking circuit includes the upper contact of the section—1 selecting relay 1401 and conductor 1406, which conductor is energized by virtue of its connection with conductor M—723 by way of contacts of relay 1608. Placing an energizing potential on conductor 1407 results also in the closure of a circuit through contacts of relays 1606, 1504, 1502, and 1501 for the stock-hundreds relay 1501. Relay 1501, upon operating, closes a locking circuit for itself to conductor 723, by way of contacts of relays 1503, 1605, 1607, and 1608; it opens its initial circuit; prepares a circuit for relay 1502; and it connects up the relays A to D of the stock-hundreds register SH to the conductors A to D of the first branch, BR1, of the impulse conductors A to D controlled by the receiving relays A to D of Fig. 14.

When the transmitter-identifying digit subsides and the receiving relays A, B, and C re-operate, the consequent removal of the energizing potential from the transfer-control conductor M—722 results in the opening of the initial circuit of relay 1405, whereupon relay 1404 operates because its upper winding is included in the locking circuit of relay 1405. When relay 1404 operates, it transfers conductor M—722 to conductor 1408, and at its four lower armatures disconnects the associated main setting conductors A, B, C, and D from the branch 2 conductors A, B, C, and D and connects them to the branch 1 conductors A, B, C, and D preparatory to the receipt of the stock-hundreds digit.

When the next quotation digit, the stock-hundreds digit, is received, the appropriate ones of the relays of the stock-hundreds register SH operate through contacts of the operated relays 1404 and 1501, registering the stock-hundreds digit. At the same time, an energizing potential is applied to conductor 1408 by way of conductor M—722 and contacts of relay 1404, thereby closing a holding circuit for the lower winding of relay 1404 and an energizing circuit for relay 1403. Relay 1403 operates and opens the locking circuit of relays 1404 and 1405, whereupon relay 1405 falls back. Relay 1404 does not fall back at this time as it is maintained operated through its lower winding.

As an additional result of the application of energizing potential to conductor 1408, a circuit is closed over conductor 1408 and through contacts of relays 1608, 1607, 1605, 1503, 1501, and 1502 for the stock-tens connecting relay 1502. Relay 1502 thereupon operates and locks itself to the locking conductor M—723 by way of contacts of relays 1504, 1606, and 1608, at the same time opening its initial circuit; prepares an operating circuit for relay 1503 at its upper armature; and at its four lower armatures it connects up the register relay of the stock-tens register ST to the second branch BR2.

When the stock-hundreds digit subsides and the energizing potential is removed from conductors M—722 and 1408, relay 1404 falls back responsive to its lower winding becoming de-

energized, again connecting up conductor M—722 to conductor 1407 and shifting the A, B, C, and D receiving conductors from branch BR1 to BR2.

When the stock-hundreds digit subsides and the energizing potential is removed from conductors M—722 and 1408, relay 1404 falls back responsive to its lower winding becoming de-energized, again connecting up conductor M—722 to conductor 1407 and shifting the A, B, C, and D receiving conductors from branch BR1 to BR2.

As the succeeding digits of the quotation continue to arrive, the impulse-reducing relays 1404 and 1405 are operated at the beginning and at the end, respectively, of each odd-numbered digit, and are restored at the beginning and at the end of each even-numbered digit, respectively, being operated and restored in the hereinbefore described manner. By this arrangement, an impulse is delivered over conductor 1407 responsive to each additional odd-numbered digit, an impulse is delivered over conductor 1408 responsive to each additional even-numbered digit. The additional impulses delivered over conductor 1407 operate the relays 1503, 1605, and 1607, successively, and the impulses delivered over conductor 1408 operate the relays 1404, 1606, and 1408, successively, while relay 1404 shifts the A, B, C, and D conductors controlled by the A, B, C, and D receiving relays from one to another of the branches B1 and B2, as hereinbefore described, resulting in each of the succeeding digits of the quotation being directed to the register of the corresponding denomination.

It is to be noted that relay 1501 is released by relay 1503 to disconnect the stock-hundreds register SH when the stock-units register is connected up; that relay 1503 is released when relay 1605 is operated to connect up the price-tens register PT to the branch 1 conductors; and that relay 1605 is released to disconnect the price-tens register from the branch 1 conductors when relay 1607 is operated to connect up the price-fractions register PF. It will be noted also that relay 1502 is released to disconnect the stock-tens register ST from the branch 2 conductors when relay 1504 is operated to connect the stock-range register to the branch 2 conductors, and that relay 1504 is released to disconnect the stock-range register SR when relay 1606 is operated to connect the price-units register PU to the conductors of branch CR2. In this way, only one register at a time is connected to each of the branches, BR1 and BR2. Then, since the main conductors A, B, C, and D controlled by the receiving relay are connected to only one of the branches at a time, the main conductors are connected to only one register at a time and they are shifted in connection with the next succeeding register following the termination of each quotation digit.

It is to be noted that labels such as "(1-3), (2-4), (3-5), and (4-6)" are applied to the transfer relays. The first digit of a label indicates the digit of a quotation to which the relay responds and the second digit indicates the quotation digit which brings about its restoration.

When the stock-units connecting relay 1503 falls back at the beginning of the fifth digit of the quotation, the price-tens digit, it connects energizing potential to the apex of the contact pyramid carried by the register relays of the stock-range register SR, enabling any selected

one of the nine associated stock-range relays of the selected group to be operated.

When the price-units connecting relay 1606 operates at the beginning of the sixth quotation digit, the price-tens digit, it places energizing potential on the starting conductor 924 of the section—1 local sender at its lower contacts, by way of contacts of connecting relay 1601, thereby starting the section—1 local sender in the hereinbefore-described manner.

When relay 1607 operates to connect up the price-fractions register PF to the branch BR1, coincident with the receipt of the seventh quotation digit, the price-units digit, it prepares a circuit for operating relay 1608 over conductor 1408, in addition to closing a locking circuit for itself and opening the locking circuit of the price-tens connecting relay 1605. The operated register relays of Fig. 15 fall back responsive to relay 1607 opening the locking circuit of relay 1605, as this operation removes energizing potential from conductor M—811.

At the close of the price-units digit, relay 1404 pulls up, thereby connecting up the first branch BR1 to receiving conductors A, B, C, and D.

Now, when the price-fractions digit is received, the concerned combination of the relays of the price-fractions register PF, Fig. 16, are operated over the conductors of branch BR1 and through contacts of transfer relay 1607. At the same time, the impulse of current placed on the transfer-control conductor M—722 is transmitted through the upper armature of the operated relay 1404 to the lower winding of relay 1404 and to the winding of relay 1403. Relay 1403 releases relay 1405, but relay 1404 is maintained operated for the duration of the impulse, as hereinbefore described. This impulse on conductor M—722 is transmitted also over conductor 1408 to relay 1608 through contacts of relay 1607. Upon operating, relay 1608 closes a locking circuit for itself directly to conductor 1408 at its inner-lower armature, at the same time opening its initial circuit. At its upper armature, relay 1608 opens the locking circuit of relays 1606 and 1607 by removing the energizing potential from conductor 1406, whereupon relays 1606 and 1607 fall back. The falling back of relay 1607 does not prematurely disconnect the relays of the price-fractions register PF from branch BR1, as the branch-connecting contacts of relay 1607 are shunted by corresponding contacts on relay 1608.

As a further result of the disconnection of energizing potential from conductor 1406, the energized section-selecting relay 1401 falls back and disconnects energizing potential from conductor 720, deenergizing connecting relays 1001 and 1201, and the left-hand winding of relay 1601. Relay 1601 remains locked up for the moment, as its right-hand winding is connected in multiple with the winding of relay 1608.

When the price-fractions digit subsides, and the energizing potential is removed from the transfer control conductor M—722, relays 1404, 1608, and 1601 simultaneously fall back, relays 1404 and 1608 placing the transfer counting chain in normal position in readiness to operate in response to the digits of the next quotation, which may now follow immediately, as hereinbefore pointed out.

Maintaining the modified receiver in synchronism with the transmitters

It is to be noted that the locking circuit for each of the relays 1401 and 1402, 1404 and 1405, 1501—1504, and 1605—1607 includes the holding conductor M—723, controlled by the slow-releasing relay M—730. It is obvious, therefore, that any operated ones of these relays must restore when relay 730 falls back to remove energizing potential from conductor 723 responsive to a pause between successive quotations.

It is to be noted that the locking circuit for relays 1404 and 1405 includes contacts of relays 1401 and 1402. By this arrangement, relays 1404 and 1405 cannot become locked up until one of the relays 1401 and 1402 has operated in response to a transmitter-identifying digit. This prevents relays 1403 and 1404 from starting out of synchronism when the digit of a new quotation arrives, following a period of unsynchronized operation of the receiver.

What is claimed is:

1. In a stock-quotation system, a pair of stock-quotation transmitters, means for operating either transmitter indefinitely to send successive quotations while the other remains at rest, a common transmission line over which said transmitters send quotations, means associated with said transmitters for introducing a time interval between successive quotations from the same transmitter, long enough to send a quotation, and means for inter-relating the sending operations of the two transmitters so that if both are in use either transmitter may transmit a quotation over the line only while the other transmitter is being delayed by the above-mentioned inter-quotation timing means.

2. In combination, a pair of senders, a transmission line over which said senders are arranged to send impulses, starting circuits for starting said senders, respectively, into operation, separate means in each sender effective when the sender is operating for preventing the closure of the starting circuit to the other sender until the operating sender has reached a predetermined point in its sending operation and for thereupon permitting the starting circuit to be closed to the other sender before the operating sender has finished its sending operation, and means in each sender for delaying the starting of the sending of impulses following the closure of its starting circuit until a sufficient time has elapsed to enable the operating sender to finish its sending operation.

3. In a signalling system, two transmitters each arranged to transmit successive series of impulses, means for operating said transmitters alternately, means controlled by each transmitter for starting the other transmitter when only a part of a series of impulses has been sent by the operating transmitter, and means in each transmitter effective upon starting for delaying the transmission of impulses a sufficient time so that the successive series of impulses transmitted from the two transmitters alternately follow each other with the same spacing between two series of impulses as occurs between any two impulses of the same series.

4. In a signalling system, two transmitters each arranged to transmit successive series of impulses, means for operating either of said transmitters either alone and entirely independent of the other transmitter to transmit series of impulses or alternately with the other

- transmitter to transmit series of impulses alternately with the other transmitter, and means effective when either transmitter fails to transmit a series of impulses in its turn for preventing the other transmitter from transmitting any impulses during the interval corresponding to the untransmitted series of impulses and for starting it when such interval expires.
5. In a signalling system, two transmitters each arranged to transmit successive series of impulses, means for operating either transmitter to send consecutive series of impulses while the other transmitter is inactive, means for operating said transmitters to transmit series of impulses alternately, and means effective when either transmitter fails to transmit a series of impulses in its turn for causing the other transmitter to delay before transmitting a further series of impulses.
10. In a signalling system, two transmitters, means in each transmitter for sending successive series of impulses, means for operating said transmitters alternately by substituting one transmitter for the other after each series of impulses, means in each transmitter for counting two series of impulses, one sent by each transmitter, and means controlled by said counting means for controlling the substitution of each transmitter for the other.
15. 6. In a signalling system, two transmitters, means in each transmitter for counting a series of impulses, means controlled by the said counting means to permit the other transmitter to start when the series is finished, means in said one transmitter for counting the impulses sent by the other transmitter, and means controlled by the second counting means to restart the first transmitter when the other transmitter has finished.
20. 7. In a signalling system, two transmitters for sending series of impulses alternately over a line, means in one transmitter for starting said transmitters to send series of impulses alternately over said line, means in each transmitter for counting
- 25

all the impulses sent by both transmitters, and means controlled by said counting means for operating said first means without interference between successive series of impulses.

9. In a signalling system, a line, two transmitters, means for operating either transmitter independently of the other to send consecutive messages over said line, means in each transmitter for introducing a delay between successive messages equivalent to a message interval, and means effective in case both transmitters are in use at the same time for causing each transmitter to send during the delay interval introduced at the other transmitter.

10. In a stock quotation system, two transmitters, a line over which said transmitters send quotations, means for allotting said line to the use of said transmitters alternately when both are in use, means in each transmitter for counting the time allotted to the other transmitter whether in use or not, and means for restricting each transmitter to the use of the line on its own time.

11. In combination, a pair of senders, a transmission line over which said senders transmit impulses, starting circuits for starting said senders, respectively, into operation, means in each sender for counting the impulses transmitted and for performing a preliminary counting operation before the first impulse is transmitted, and means in each sender effective when the same is operated for preventing the closure of the starting circuit to the other sender until the time required to complete the remaining portion of the sending operation of the operating sender becomes equal to the time required for the preliminary counting operation in the other sender and for thereupon permitting the starting circuit to the other sender to be closed, whereby if the other sender is ready to start it can start sending impulses without a break in the continuity of impulse transmission over said line.
